(57) **CLAIM**

The ornamental design for a kiosk, as shown and described.

DESCRIPTION

FIG. 1 is a front perspective view of a kiosk;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is a perspective view of the kiosk of FIG. 1, shown in a state of use with an additional environmental stand; and, FIG. 10 is another perspective view of the kiosk of FIG. 1, shown in a state of use with an additional environmental stand.

Broken lines showing a stand for a kiosk in FIGS. 9 and 10 depict environmental subject matter and form no part of the claimed design. All other broken lines seen in the drawings depict portions of the kiosk that form no part of the claimed design.

1 Claim, 8 Drawing Sheets
